WINDOW VENTILATOR

Filed Dec. 30, 1925

Edward L. Clarke

334 C. R. Wright Jr. Attorney

UNITED STATES PATENT OFFICE.

EDWARD L. CLARKE, OF SCRANTON, PENNSYLVANIA.

WINDOW VENTILATOR.

Application filed December 30, 1925. Serial No. 78,404.

My invention relates to improvements in window ventilators to be used any place where such a ventilator is suitable.

The object of my invention is to provide a 5 window ventilator adapted for the upper sash so the sash can be lowered from the top and air passing to the place is diverted towards the ceiling.

The invention pertains particularly to a 10 ventilator which is automatically brought into operative position by the lowering of the upper sash and moved upwardly out of the way when its use is not desired by raising the upper sash.

15 Another object of my invention is to provide a ventilator of this character which can be readily attached to any ordinary window without any modification or change thereof, and at the same time producing a very simple, cheap and effective ventilator having certain details of structure and combination of parts hereinafter more fully described.

In the accompanying drawings:—

25 Figure 1 is a perspective view of a window frame and sash showing my improved ventilator applied thereto.

Figure 2 is a vertical sectional view of 30 Figure 1, showing the upper sash lowered and the ventilator in its operative position and showing it in dotted lines when the sash is raised.

35 Referring now to the drawings, the numeral 1 represents the frame of a window, and 2 the lower sash, and 3 the upper sash, all of which are of the usual construction. Secured to the upper part of the upper sash on the inner face are the two hinges 4 and 5, so constructed as to operatively support the 40 deflecting board or plate 10 carried thereby. The deflecting board has its lower part cut at an angle as indicated at 18 and its upper part rounded as indicated at 17 as clearly shown in Figure 2 of the drawings.

45 The hinge consists of leaf 7 which is fastened to the upper inner face of the upper sash by means of clamps and set screws and has pivotally connected thereto at 8, the long leaf 9 which when the window is closed assumes the position shown in dotted lines in 50 Figure 2 of the drawings. Secured to the upper face of these two long leaves of the two hinges is a metal or wooden plate 10, which is of a width slightly less than the length of the long leaf 9, whereby it is rigidly carried by the leaves and moves there-

with as will be later described. The long leaf 9 has pivotally connected at 11 the short leaf 12 and pivotally connected at 13 to the short leaf 12 is another leaf 14 which is secured to the inner face 15 of the frame by means of screws or the like. The hinges 4 and 5 as shown in Figure 1 of the drawings, are spaced some distance apart so as to more firmly support the deflecting plate 65 10.

The several parts when the window is closed assume the position shown in dotted lines in Figure 2 of the drawings. The deflecting plate is arranged so that its lower 70 part is comparatively close to the upper edge of the upper sash. Upon lowering the upper sash the leaf 9 gradually moves downwardly in an inclined position carrying with it the short leaf 12 rocking it upon its pivots 11 and 13. By the time the sash has passed from the usual groove 16 in the frame, the deflector plate 10 carried by the links has assumed an inclined position, and air entering above the sash is diverted in an 75 upward direction in the room. The more the window is opened, the more the link 9 travels down increasing the opening on the outer side between the frame and the lower part of the deflector plate 10, but at all times 80 assumes an inclined position. The continued downward movement brings the leaves 9 and 12 in alinement, and the sash is lowered as far as possible when this ventilator is attached, as the hinges limit the 85 movement thereof. In this position, the space between the lower part of the deflector plate 10 and the frame on the outer side is considerable, and allows a considerable amount of air to pass into the room, but 90 owing to the inclination of plate 10 is diverted upwardly towards the ceiling.

95 By this structure it will be seen that I have produced a very effective ventilator which is wholly automatic and which when 100 the upper sash is closed, folds up within the frame and forms a neat appearance.

It will be understood that hinges can be disconnected from the sash when for any purpose the free movement of the upper 105 sash is desired, and in which event it will hang suspended from the top of the window frame.

110 While I have shown and described this specific construction, it will be understood that slight variations could be made therein without departing from my invention.

Having thus described my invention what I claim is:—

1. The combination with a window frame and sash, multiple leaf hinges connecting the sash and frame and a deflector plate carried by the hinges whereby the plate is raised and lowered with the sash, and always assumes an inclined position when the sash is lowered to admit and divert air in an upward direction over the sash.
2. The combination with a window frame and sash, of multiple leaf hinges connecting the upper end of the sash, and the inner face of the frame, and a deflector plate carried by the hinges whereby the plate is raised and lowered with the sash and always maintained in an inclined position when the sash is lowered to admit and divert air in an upward direction over the upper sash.
3. The combination with a window frame and sash, of multiple leaf hinges connected to the upper end of the sash and to the window frame, and a deflector plate carried by the hinges so arranged that the deflector plate assumes practically a horizontal position against the frame when the sash is raised, and assumes an oblique position at any open position of the sash to admit and divert air in an upward direction over the sash.
4. The combination with a window frame and sash, four leaf hinges connected to the upper end of the sash and to the inner face

of the window frame, a deflector plate carried by the leaf next to the leaf connected to the sash, whereby the deflector plate assumes an approximately horizontal position against the frame when the sash is closed, and assumes an oblique position when the sash is lowered to admit and divert air in an upward direction over the sash.

5. The combination with a window frame and sash, four leaf hinges having the end leaf of each hinge connected to the upper inner face of the upper sash, the other end leaf of each hinge connected to the inner vertical face of the window frame, a deflector plate carried by the leaves next to the leaves connected to the sash, whereby the deflector plate assumes an approximately horizontal position against the frame when the sash is raised, and assumes an oblique position when the sash is lowered to admit and divert air in an upward direction over the upper sash.

6. The combination with a window frame and sash; of a deflector plate pivotally connected to the upper edge of the sash, and a link pivotally connected to said deflector plate and to the upper end of said window frame, said link controlling the movement of said deflector plate in the movement of said sash.

In testimony whereof I have signed this specification.

EDWARD L. CLARKE.
